UNITED STATES PATENT OFFICE.

JOHN W. WILLINGHAM, OF HONOLULU, TERRITORY OF HAWAII.

ASH-TRAY.

1,348,676.

Specification of Letters Patent. Patented Aug. 3, 1920.

Application filed June 24, 1919. Serial No. 306,315.

To all whom it may concern:

Be it known that I, JOHN W. WILLINGHAM, a citizen of the United States, residing at Honolulu, in the Territory of Hawaii, 5 have invented new and useful Improvements in Ash-Trays, of which the following is a specification.

This invention relates to smokers' articles, particularly to ash trays, and has for its 10 object the provision of an ash tray provided with means whereby a cigarette may be extinguished, it being well known that most brands of ready made cigarettes after being ignited will burn until entirely consumed, 15 the present invention being designed to economize in the use of cigarettes by preventing the cigarette from being entirely consumed while lying idle.

Another object is the provision of a device 20 of this character which by providing means for extinguishing cigarettes will not only economize in the use of the cigarette but will also prevent damage which so often results from leaving a burning cigarette 25 upon the edge of a table or the like.

More specifically, the invention resides in the provision of an ash tray including a main portion constituting the receptacle, and an auxiliary portion in the nature of a 30 flange arranged in somewhat spaced relation to the main portion whereby to provide a space into which the lighted end of a cigarette may be thrust for extinguishing the fire.

35 An additional object is the provision of a device of this character which will be extremely simple and inexpensive in manufacture, neat in appearance, efficient in service, durable in use, and a general improvement 40 in the art.

With the above and other objects and advantages in view, the invention consists in the details of construction to be hereinafter more fully described and claimed, and illustrated in the accompanying drawings, in 45 which—

Figure 1 is a plan view of an ash tray constructed in accordance with my invention, Fig. 2 is a cross sectional view there-

50 through, and Fig. 3 is a sectional view taken at right angles to Fig. 2.

Referring more particularly to the drawing, the numeral 10 designates the main portion of the device which is formed preferably, though not necessarily of sheet metal

and which is formed to provide a base bearing 11 which may be merely a flange formed at the outer periphery of the main receptacle, this main receptacle, whether formed 60 solid or of sheet metal, is provided adjacent its outer periphery with a circumferential groove or recess 12 which is adapted to serve as a receptacle for ashes, match stems, and the like. 65

Disposed upon the center of the upper portion of the main receptacle 10 is a washer 13 upon which is disposed the centrally depressed portion 14 of a circular or disk-like member 15 which is dish-shaped 70 in cross section and which has its outer edge preferably beaded or rolled, as shown at 16. The shape of the member 15 is such that it extends upwardly with respect to the central portion of the main member 10, as clearly 75 shown, whereby to form a gradually inwardly constricted circumferential opening 17.

Disposed upon the center of the depressed portion 14 of the disk member 15 is a standard 80 18 which is secured in place by means of a screw 19 which passes upwardly through the center of the main member 10, through the center of the depressed portion 14, and into the standard 18. At its upper end, the 85 standard carries a safety match box holder of convenient type formed preferably of two U-shaped members 20 and 21 secured together in inverted relation, as is well known in the art. 90

In the use of the device, the match box holder formed by the U-shaped members 20 and 21, which really forms no part of the present invention, is adapted to support a box of safety matches in the ordinary manner. Fresh or unlighted cigarettes may, if desired, be disposed within or upon the dished disk member 15 around the standard 18. As previously stated, the circumferential groove 12 in the main member is adapted to receive ashes, match stems, and the like. When the user of a cigarette desires to extinguish the same in order to economize in the consumption of the cigarette, or for any other reason, it is merely necessary that 100 he insert the burning end into the constricted opening 17 between the top of the main member and the disk member 15. This act will suffice to smother or choke the cigarette by mashing the lighted end and it 105 will be apparent that all the burning tobacco may, if desired, be removed from the 110

remainder of the cigarette by proper manipulation of the cigarette within constricted opening.

From the foregoing description and a study of the drawing it will be apparent that I have thus provided a neat appearing and extremely simple and inexpensive ash receiver which is so constructed that a burning cigarette may be extinguished so as not to 5 only to economize in the use of the same but also to avoid the burning of table cloths, edges of tables, and the like, as so frequently occurs when a burning cigarette is laid down.

15 While I have shown and described the preferred embodiment of my invention it is of course to be understood that I reserve the right to make such changes in the form, construction, and arrangement of parts as will 20 not depart from the spirit of the invention or the scope of the subjoined claims.

Having thus described my invention, I claim:—

1. An ash tray comprising a main member 25 provided with a circumferential groove in

its upper face serving as a receptacle for ashes and the like, a cupped member secured centrally upon said main member and having its sides extending upwardly in diverging relation to the top of said main member 30 whereby to provide an inwardly constricted circumferential opening.

2. An ash tray comprising a main member provided in its top surface with a circumferential groove serving as a receptacle for 35 ashes and the like, a cupped member disposed centrally upon said main member and having its sides extending upwardly in diverging relation to the top of said main member whereby to provide an inwardly 40 constricted circumferential opening spaced inwardly from the circumferential groove in said main member, a standard extending upwardly from the center of said cupped member and adapted to support a match 45 box holder, and a screw passing upwardly through the center of said main member, said cupped member, and into said standard.

In testimony whereof I affix my signature.

JOHN W. WILLINGHAM.
